UNITED STATES PATENT OFFICE.

CLYDE DAVIS AND CHARLES E. HARDING, OF SIOUX FALLS, SOUTH DAKOTA.

BED-TRAY AND DRESSING-TABLE.

1,298,672.

Specification of Letters Patent.

Patented Apr. 1, 1919.

Application filed February 23, 1918. Serial No. 218,824.

To all whom it may concern:

Be it known that CLYDE DAVIS and CHARLES E. HARDING, citizens of the United States, residing at Sioux Falls, in the county 5 of Minnehaha and State of South Dakota, have invented certain new and useful Improvements in Bed-Trays and Dressing-Tables, of which the following is a specification.

10 This invention is an attachment for a bed and is more particularly adapted for the use of invalids either at home or in the hospital and may be used for serving meals or as a support for instruments and dressing 15 during surgical operations so that articles placed thereon will be conveniently accessible for use as required, and when not desired for use it may be readily carried beneath the bed in such a position as will permit 20 it to be immediately swung to the operative position with little effort.

In most of the devices in common use, the arrangement of parts is such that when not in use, the device is still in evidence and 25 usually more or less in the way. It seems customary in providing attachments to make them in such a manner that when the need has passed, they must be either removed bodily from the bed or else swung to one side 30 where they may still be seen.

The utility of such devices is great and they are especially valuable when it is desired to serve meals to a patient or it becomes necessary to give attention to personal 55 hygiene, or to hold articles usually employed in surgical cases, either during the operation or in changing the dressings thereafter.

One object of this invention is to provide an adjustable tray and table that may be 40 quickly and easily placed in an operative position for use and which may be as quickly and easily placed in an inoperative position and out of the way in a more or less concealed position ready for immediate use 45 should it be required.

Another object of this invention is to provide a tray and surgical dressing table and instrument table adapted for bed use that may be attached to the bed at different 50 places without disturbing the bed clothing and at the same time leave sufficient space between it and the patient.

A further object of this invention is to provide a slideable table and tray mounted in 55 suitable guides and carried by rotatable supports connected to a rail of a bed and re-

tained in a plurality of positions both operative and inoperative.

A still further object of this invention is to provide a bed with an adjustable table and 60 tray, that when in use may be supported for use over the bed and patient or occupant, and when the service has been rendered or finished, may be placed beneath the bed in a position ready for immediate use without disturbing the patient or disarranging the bed 65 clothing.

Broadly stated the invention comprises a plurality of clamps adapted to be removably secured to the rail of a bed, a support rotatably mounted at one end of each of the clamps, a guide element rotatably mounted adjacent the upper end of each of the supports, a supporting member adapted to slide in the guides, a brace and stiffening member 70 secured to the under surface of the supporting member, an engaging element mounted adjacent one end of said supporting member, stops on said member for limiting its movement relative to the guides, means on the 75 supports for preventing rotation of the guides, a bar extending between the clamps to hold them in a spaced relation, and a curved arm rotatably mounted on said bar and having its free end adapted to engage 80 with the brace or stiffening piece mounted upon the under side of the supporting member when in one position, said arm serving as a stop means when the supporting member 85 is placed in an inoperative position, means 90 for maintaining the arm in a plurality of positions with respect to said bar, said supports being rotatably mounted in the clamps are thus adapted to swing in vertical planes 95 so that the supporting member may be placed beneath the bed at which time the arm may be engaged with one end of said member to prevent movement in the guide, and means for retaining the clamps in a plurality of positions with respect to the rail. 100

One practical form of construction and assembly will be described and illustrated in the accompanying drawings, in which:

Figure 1 is a side elevation of a bed with the tray and table secured thereto so that 105 the support member is in an operative position, the dotted lines showing other positions relative to the rail of the bed,

Fig. 2 is a partial vertical sectional view of a bed showing the table and tray in the 110 same position as illustrated in Fig. 1,

Fig. 3, is a top plan detail of one of the

guide members with a portion of the supporting member with one of the stops thereof in engagement with the guide member, and

- 5 Fig. 4 is a sectional view through the boss or hub of the arm carried on the bar between the clamps.

In the preferred embodiment about to be described a bed having a head board 5 and 10 a foot board 6 is provided. The head and foot boards may be joined in the usual way by means of the rails, one of which is shown at 7. This rail 7 is of the usual L-shape in cross section such as is customarily 15 employed with beds of the brass or iron type. The rail 7 may be connected with the foot and head boards in any usual or customary manner.

In order to clamp the device securely to 20 the rail 7 two clamps are employed that are formed of the sections 8 and 9. These sections are approximately L-shape and when clamped together provide a recess that is shaped to conform to the cross section of 25 the rail 7. The two sections 8 and 9 may be held together by any usual means such as the bolts 10. The section 8 is preferably provided with a bearing indicated at 11. As each of the clamps are similarly formed 30 the bearings 11 will have their holes in alignment.

Extending between the sections 8 of the clamps there is a bar 12 that may be rigidly secured in the bosses 13. If desired this 35 bar 12 may be provided centrally with the splines 14 and 15. These splines or ribs are preferably spaced diametrically as shown in section in Fig. 4. These ribs or splines 14 and 15 are adapted to coöperate with a boss 40 or hub 16 that has suitable key ways cut therein, said boss or hub being mounted upon the bar 12. From the boss or hub 16 there springs an arm 17 that is provided at its free end with a projection 18 to serve as 45 an engaging member.

In each of the bearings 11 there is rotatably mounted a support 19 that is approximately U-shaped. The lower or vertical limb is rotatably mounted in the bearing 11. 50 The upper end has rotatably mounted thereon a suitable guide member 20 that is provided with a slot 21. As shown the guide member 20 is approximately L-shaped and is provided with a rounded end 22 having a 55 bearing therein to coöperate with the other vertical limb of the support 19.

As shown the slot 21 projects horizontally in a manner to coöperate with the guide member 23 carried by the other support. 60 These guide members and their slots serve to slidably mount a table or tray 24 which acts as a supporting member. In order to provide stiffness for this supporting member 24 a brace 25 is secured to the under 65 surface thereof. As shown this brace 25 is

preferably T-shaped in cross section and the vertical limb tapers and has its greatest height at the retained end of the supporting member.

The vertical portion which may be indicated at 26 is adapted to engage with the projection 18 carried at the end of the arm 17. If desired suitable notches or other usual means may be employed.

The supporting member 24 is provided at 75 the opposite end with a U-shaped engaging member 27. This member 27 is adapted to engage with the projection 18 when the supporting member 24 is moved to the left as shown by the dotted lines in Fig. 2. This 80 will serve to hold the member 24 against sliding movement or accidental return to the full line position. This will provide for extending and retaining the article supporting member 24 over the adjoining bed. One 85 edge of the supporting member 24 may be provided with the spaced stops 28 and 29. These stops are adapted to engage with the sides of the guide member 20 one being shown in engagement in Fig. 2. These 90 stops serve to limit the movement of the supporting member 24 in its sliding relative to the guides 20.

The guide members 20 may be provided with a suitable locking arrangement generally indicated at 30. This lock may be of any usual type of construction that will serve to maintain the guides immovable with respect to the supports 19. This is done to prevent rotation of the guide member 100 when it is desired to hold the supporting member 24 in its operative position as when extended over the bed. 95

In Fig. 2, as shown by the dotted lines, the supporting member 24 may be slid to the 105 left through the guides 20 and 23 until the stop 28 engages with the guide 20. The projection 18 carried by the arm 17 may then be disengaged from the engaging member 27. The locking device 30 is then released 110 whereupon the supports 19 may be rotated in their bearings 11 and their other ends rotating in the bearings 22 of the guide members so that the supporting member 24 will be maintained in a horizontal position during such movement. 115

The continuing of this movement will place the supports 19 so that the guide members 20 and 23 are below the rail 7 as shown by the dotted lines in Figs. 1 and 2. 120 The projection 18 being disengaged from the member 27, the arm 17 may then be swung so that the projection 18 will engage with one end of the support 24, as shown by the dotted lines. For this purpose the projection 18 extends from arm 17 in such a manner that an angle or shoulder is formed therebetween that will coöperate with the end of the member 24.

In order to provide for movement of the 130

5 arm 17 it is adapted to slide on the bar 12 until it disengages with the splines or ribs 14 and 15 whereupon it may be rotated so as to extend downward in the opposite direction as shown in the dotted lines in Fig. 2. When the arm is moved back to engage with the splines or ribs 14 and 15 it will be firmly held against rotation and this will prevent any movement of the member 24.

10 As shown in the several figures the table or tray is adapted to be positioned over the bed and above the patient so as to provide clearance therebetween. Fig. 2 may be considered the operative position. The supporting member 24 will then be rigidly held against undue movement and the brace 25 extending longitudinally thereof tends to stiffen it. The arm 17 by engaging with the vertical portion 26 of the brace will further 20 serve to support the member 24. As this arm 17 is curved it does not interfere with the bed clothing in any way.

The dotted lines in Fig. 2 show how the supporting member 24 may be positioned beneath the bed in the inoperative position. This placing of the table or tray will permit its being immediately available for use. The supporting member 24 may carry, from the operative to the inoperative position such 30 articles as it may be desired to have convenient for future dressings if employed with a surgical case.

What we claim is:

1. A tray and dressing table, which 35 comprises spaced supports rotatably connected with the rail of a bed, a slidable article supporting member mounted in guides carried by the supports, means for limiting the travel of the supporting member, means for 40 retaining said member in a plurality of positions, and a rotatable brace extending beneath the supporting member and operatively connected with the spaced supports, said member being supported horizontally 45 in each position.

2. A tray and dressing table, which 50 comprises clamps adapted to be connected with the rail of a bed, spaced supports rotatably mounted in the clamps, said supports being 55 rotatable in a vertical plane, guide elements rotatably connected to and carried at the free ends of the supports, a supporting member slidably mounted in the guides, stops for limiting the movement of the member 60 in the guides, locking means for preventing rotation of the guide elements, and a rotatable arm serving as a support and lock for the slidable supporting member co-operatively connected with the clamps, the rotatable mounting of the supports permitting the supporting member to be positioned over

the bed and beneath the bed in a horizontal plane.

3. A bed tray and surgical dressing table, which comprises spaced supports connected 65 with a rail of a bed and adapted to rotate in parallel vertical planes, a supporting member slidably connected with the supports, a longitudinally extending brace operatively connected with the supports, and 70 means locking the supports and supporting member in a plurality of positions, said supporting member being maintained horizontal in each position.

4. A bed tray and surgical dressing table, 75 which comprises spaced clamps adapted to be removably secured to the rail of a bed, a bar extended therebetween, a support rotatably mounted in each clamp and capable of swinging in parallel vertical planes, 80 guides rotatably mounted adjacent the upper ends of the supports for movement in vertical planes independently of the movement of the supports, an arm rotatably mounted on the bar and provided with an engaging end, 85 a supporting member slidably mounted in the guides adapted for co-operation with the engaging end of the arm when in a plurality of positions, spaced stops on the supporting member for limiting the travel of 90 said member, means carried by the guides for preventing their rotation on the support, said supports upon rotation being adapted to position the supporting member 95 in a spaced relation to the upper surface of the bed in an operative position or spaced beneath it in an inoperative position.

5. A bed tray and surgical dressing table comprising spaced clamps adapted to be removably secured to the rail of a bed, a bar 100 extended therebetween, a support rotatably mounted in each clamp and capable of swinging in parallel vertical planes, guides rotatably mounted adjacent the upper ends 105 of the supports for movement in vertical planes independently of the movement of the supports, a supporting member slidably mounted in the guides, and an arm rotatably mounted on the bar and provided on the end with a right angle extension, said 110 right angle extension adapted to engage the under side of the supporting member when in one position and the end of the supporting member when in another position.

In testimony whereof we affix our signatures in presence of two witnesses.

CLYDE DAVIS.
CHARLES E. HARDING.
